UNITED STATES PATENT OFFICE.

HENRY B. BROWN, OF NEW YORK, N. Y., ASSIGNOR TO WESTERN ELECTRIC COMPANY,
INCORPORATED, OF NEW YORK, N. Y., A CORPORATION OF NEW YORK.

TELEPHONE SYSTEM.

Application filed June 13, 1924. Serial No. 719,750.

This invention relates to telephone systems, and more particularly, to a system wherein connections are established by means of automatic switching apparatus.

5 The object of this invention is to connect a calling line in a manual office with any desired line in a mechanical office by merely depressing in succession the proper office or route key and one or more of a single group 10 of ten keys numbered from 0 to 9.

In accordance with this invention each operator in a manual telephone office is provided with a group of ten keys one for each of the digits 0 to 9, and a group 15 of office keys one for each office to which she has access. To reach any line in any distant office to which she has access the operator merely depresses the proper office key and then proceeds to write 20 up in succession upon the ten keys, the digits comprising the number of the called line. The digits thus written up are recorded by a register sender. Depressing the office key, causes one of a group of circuits, called link 25 circuits, to simultaneously hunt for and seize the calling operator's position, an idle trunk to the desired office, and an idle register sender.

When an idle trunk is found, the number 30 of the seized trunk is visibly indicated to the operator. The registers in the sender are set in succession in accordance with the digits comprising the number of the called line, and after the second digit has been 35 recorded in the register sender and an idle trunk circuit has been found, the first digit is transmitted over the trunk circuit in the form of impulses and one of a train of switches at the distant mechanical office is 40 set. When the third digit has been recorded the second digit is transmitted over the trunk circuit, and so on. When the last digit is recorded, the plug of a cord is inserted in the jack of the trunk circuit, and 45 the digit last recorded is then transmitted over the trunk circuit. The called line, if idle, is seized, and is signaled, and upon responding conversation takes place in the ordinary manner. When the last digit is 50 recorded, the position equipment is discharged, and when the last digit is transmitted, the register sender is also discharged.

When the conversation is completed disconnect signals are given to the operator, and disconnection takes place in the ordinary way. 55

A feature of this invention is the arrangement whereby the operator may at will call any line, consisting of any number of digits, 60 as desired.

Another feature of this invention is the arrangement whereby the digits are recorded and the proper selections in accordance therewith take place simultaneously, one digit, however, always being held in reserve 65 until the operator indicates that all digits have been recorded.

Other features will appear from the detailed description which follows: In the drawings comprising ten sheets numbered 70 Figs. 1 to 11 which are placed as indicated in Fig. 11, the invention is schematically set forth.

Fig. 1 represents a calling subscriber's line in a manual office and a typical cord 75 circuit commonly used in establishing a connection between the calling line as indicated and any called line.

Fig. 2 represents the allotter circuit for allotting an idle link circuit such as is disclosed in Figs. 4 and 5. 80

At the left of Fig. 3 a steering switch is shown, which is used in routing a connection to a trunk finder switch such as the one shown in the center of Fig. 3, or at the right 85 of Fig. 4.

In Fig. 5 a position finder switch and a sender selector switch are also shown. The trunk finder switch (Fig. 3 or 4), position 90 finder switch (Fig. 5) and sender selector switch (Fig. 5) are all controlled by the link circuit (Figs. 4 and 5) so that as soon as a call is initiated, the link circuit functions causing the trunk finder switch, position finder switch and sender selector switch 95 to operate simultaneously to find respectively, the first idle trunk, the calling position and an idle sender.

Fig. 6 shows the office and numerical keys, and Fig. 7 the position indicating equipment, which is used to indicate to the operator the number of the trunk seized by the trunk finder. It should be understood 100 that there is one office key, similar to the key

610, for each distant mechanical office to which the operator has access.

In the upper right-hand corner of Fig. 3 and in Fig. 8 are shown two trunk circuits, such as are used in establishing a connection to the distant mechanical office (Fig. 8).

Figs. 9 and 10 show the register sender equipment, consisting of a group of registers which are set in various combinations under control of the numerical keys (Fig. 6) to operate the counting relays (Fig. 10) which count off the number of impulses transmitted over the trunk circuit to the distant mechanical office for setting the automatic switches thereat. An interrupter shown at the upper right-hand corner of Fig. 9 is used for producing the impulses required. The sender is also provided, as indicated at T. S., Fig. 9, with a timing switch for measuring off a definite time interval between each train of impulses transmitted to the distant office, to permit the switch at the distant office to have sufficient time to trunk hunt before another series of impulses is transmitted; a recording switch which advances one step for each digit recorded by the operator to transfer the register leads from one group of registers to the next succeeding group; and a sending switch which is operated by the interrupter to control the transmission of impulses to the distant mechanical office.

Answering call.

When the receiver is removed from the switch-hook at the substation 1, (Fig. 1) the line relay 2 operates over an obvious circuit including the substation loop, and the line lamp 3 is lighted. The plug of the cord 6 is inserted in the jack 5 operating the cut-off relay 4, thereby opening the circuit through the line relay 2 which releases extinguishing the line lamp 3. The supervisory relay 18 is operated thereby preventing supervisory lamp 17 from lighting. Listening key 8 is operated, connecting the operator's telephone set to the calling substation 1. The calling substation 1 gives the number of the desired line which we will assume to be the substation 800, (Fig. 8), in a distant central office of a full mechanical step-by-step system.

Operating link circuit.

The key 610 (Fig. 6), which is designated by a code corresponding to the central office (Fig. 8), is depressed by the operator, closing a circuit to operate relays 613 and 619 as follows: battery, armature 633 of relay 618, 634, right winding of relay 619, 635, left winding of relay 613, 636, 637 to ground. Relays 619 and 613 operated lock by way of 658, 648 and 647 to ground. The operation of the office key 610, also closes an obvious

circuit to operate relay 612. When the office key 610 is released, relay 611 operates in series with the winding of relay 612 and relays 611 and 612 lock in series to ground at armature 669 of relay 619.

There is a group of link circuits for each trunk route to which the operator has access, and an idle link circuit is always pre-selected by the selector switch of the allotter circuit so that the brushes 230 to 235 inclusive of the selector switch in Fig. 2 are normally resting upon the terminals of an idle link circuit, which we will assume to be the link circuit shown in Figs. 4 and 5. Under these circumstances the operation of relay 613 will close a circuit to operate relay 200 (Fig. 2) as follows: battery, armature 638 of relay 614, 639, 625, 501, 204, resistance 201 in parallel with the winding of relay 200 and resistance 202 in series, to ground. Relay 200 operated operates relay 205 as follows: battery, 206, 207, 208, winding of relay 205, 209, 210 to ground. Relay 205 operated locks by way of its armature 239 to ground and operates relay 246 over an obvious circuit. Relay 246 operated opens at 210 the ground to the winding of relay 238 associated with the bridge 236 thereby preventing relay 238 from operating thus rendering bridge 236 ineffective, until the first bridge 250 has performed its function, after relay 246 releases.

When the interrupter 251 is closed relay 247 operates over the following circuit: battery, armature 248 of relay 211, winding of relay 247, 249, 259, interrupter 251 to ground. Relay 247 operated connects ground by way of 257 to the winding of relay 258 but the latter does not operate at this time as it is short-circuited by the ground at interrupter 251. When the ground at interrupter 251 is opened, relay 258 operates, and locks in series with relay 247. Relay 205 operated operates relay 508 (Fig. 5) over the following circuit: battery, winding of relay 508, 566, 245, 235, 216, 215, 214, 213, 212 to ground.

The next time ground is connected to 249 by interrupter 251, relay 252 operates to operate relay 261 and start the trouble alarm signal 253 unless relay 211 has operated in the meantime as hereinafter described.

Relay 508 operated locks by way of 576, 586 and 589 to ground, and closes a circuit to operate relay 509 as follows: battery, winding of relay 509, 510, 511, 512, 513 to ground; and a circuit to operate relay 417 as follows: battery, left winding of relay 417, 416, 595, 510, 511, 512, 513, to ground. The function of relay 417 will be hereinafter described. Relay 509 operated locks as follows: battery, winding of relay 509, 526, 527, 400, 401, 402, 403, 404, 528, 529, 512, 513 to ground. Relay 509 operated con-

nects battery to the network consisting of resistances 201 and 202 and the winding of relay 200 as follows: battery, armature 519 of relay 588, 518, 517, 516, 515, 514, 500, 5 203, 202 to ground.

It will be recalled that a circuit was closed when relay 613 operated by way of 625 and 204 to operate relay 200. When relay 509 operates as previously described, 10 the circuit including the resistance 202 by way of 203, 500, etc., balances the circuit including the resistance 201 by way of 204, 501, 625, etc., and thus the potential at 255 and 256 is substantially the same hence relay 200 releases, opening at 206 the circuit through relay 205 which also releases.

Relay 509 operated also closes a circuit to operate relay 523, as follows: battery winding of relay 523, 524, 525, 526, 527, 400, 20 401, 402, 403, 404, 528, 529, 512, 513 to ground. Relay 523 operated locks by way of 537, 512 and 513 to ground.

The stepping magnet 227 now operates over the following circuit: battery, winding of the stepping magnet 227, 226, 217, 218, 219, 228, 229, brush 230, 240, 520, 521, 522 to ground. Relay 211 operates in parallel with the stepping magnet 227, and opens at 248 the circuit through relays 247 and 258 which release. These operations all take place only in case the call is progressing properly before interrupter 251 is again closed so that relay 252 will not ordinarily have a chance to operate and by operating relay 261 start the trouble alarm 253.

Preselecting an idle link.

The stepping magnet 227 operated, opens at 226 its own operating circuit, thus releasing and stepping the brushes 230 to 235 inclusive one step in an anti-clockwise direction. If the next link circuit similar to that shown in Fig. 5 to which the brushes 230 to 235 inclusive are now connected is busy, the relay corresponding to relay 523 will be operated and ground will be connected by way of its lead corresponding to lead 240 to the brush 230 and the circuit to operate the stepping magnet 227 will 40 again be closed causing it to operate and again release and rotate the brushes 230 to 235 inclusive another step. This cycle of operations continues until the next idle link circuit is found, in which case the relay in such link circuit corresponding to relay 523 will not be operated, hence ground will not be connected to its lead corresponding to lead 240, and the circuit to operate the stepping magnet 227 being open, the magnet 45 will not reoperate, and relay 211 will release. As long as the stepping magnet 227 is operating and releasing, relay 211 which is slow to release remains operated and by 50 removing ground at 212 from brushes 235 or 231 as the case may be prevents the re-

lays in the preselected link corresponding to relays 508 or 598 from operating until an idle link circuit has been found and the allotter circuit Fig. 2 is again normal. In this manner, an idle link circuit if available 70 is always preselected by the allotter circuit, Fig. 2.

Finding the operator's position.

Relay 523 operated also closes a circuit to 75 operate relay 538 as follows: battery, left winding of relay 538, 546, 521, 522 to ground. Relay 538 operated locks as follows: battery, right winding of relay 538, 547, 548, 549, 559, brush 540, 596, 513 to ground. Relay 80 523 also closes a circuit to start the operation of relay 408 as follows: battery, winding of relay 408, 476, 521, 522, to ground. The function of relay 408 which is designed to be very slow to operate, is hereinafter more 85 fully described. Relay 538 operated closes a circuit to operate relay 539 as follows: battery, left winding of relay 539, 569, 579, 589 to ground. Relay 539 operated locks as follows: battery, right winding of relay 90 539, 5010, 521, 522 to ground. A circuit is now closed to operate the stepping magnet 536 of the position finder switch as follows: battery, winding of the stepping magnet 536, 558, 568, 578, 569, 579, 589 to 95 ground. The stepping magnet 536 operated opens at 555 its own operating circuit thereby releasing, and causing the brushes 540 to 545 inclusive to rotate one step in an anti-clockwise direction. The function of the 100 positon finder switch with which the stepping magnet 536 is associated is to find the particular position whose operator is attempting to establish a connection with the step-by-step central office shown in 105 Fig. 8.

Relay 613 of every operator's position except the position we are seeking will be normal hence ground will be connected to every terminal in the arc 530 except the terminal to which lead 502 is connected which will be connected by way of 626, 657, left winding of relay 614, and 633 to battery. The relay 538 will remain locked over bridging brush 540 to ground on the various terminals in the arc until brush 540 comes to rest upon the terminal to which lead 502 is connected when relay 538 releases, opening at 579 the circuit of the stepper magnet 536 whose brushes 540 to 545 inclusive 115 now remain at rest upon the terminals associated with the operator's position shown in Fig. 6. Relay 538 released closes a circuit to operate relays 405 and 614 as follows: battery, armature 633 of relay 618, left 120 winding of relay 614, 657, 649, 626, 502, 540, 559, 549, 548, 547, 557, 556, 406 winding of relay 405, 407, 567, 577, 587 to ground. The ground now supplied to brush 540 through 125 the winding of relay 405 causes the opera- 130

tor's position to test busy to all other position finder switches which may be hunting at this time or at any time while this call is progressing.

5 Relay 405 operated closes a circuit to operate relay 588 as follows: battery, winding of relay 588, 599, 409, 418, 419, 402, 403, 404, 528, 529, 512, 513 to ground. Relay 614 operated locks through its right winding by way of 648 and 647 to ground and opens at 638 the battery supplied by way of 625 and 204 to the resistance 201 of the bridge network (Fig. 2). The operation of relay 614 opens at 648 the holding circuit through 10 the left winding of relay 613 but the latter relay remains locked over the following circuit: battery armature 633 of relay 618, 634, left winding of relay 619, right winding of relay 613, 657, 649, 626, 502, 540, 559, 549, 20 548, 547, 557, 556, 406, winding of relay 405, 407, 567, 577, 587 to ground. Relay 588 operated, opens at 519 the battery supplied by way of 500 and 203 to the resistance 202 of the bridge network (Fig. 2), and closes 25 the following circuit to operate relay 575: battery, 519, winding of relay 575, 525, 526, 527, 400, 401, 402, 403, 404, 528, 529, 512, 513, to ground. The function of relay 575 will be described in detail under "selecting 30 an idle sender". Battery is removed from leads 625 and 204 under control of relay 614 slightly in advance of the removal of battery from leads 500 and 203 by the operation of relay 588. This precaution is taken 35 to prevent the unbalancing of the bridge network from momentarily reoperating relay 200.

It should be observed that only the position finder switch associated with the stepping magnet 536 is used at this time. There are five position finder switches of which 40 three are omitted from the drawing (Fig. 5) only the first and last switches being shown. Since each switch has a capacity of twenty operators the total capacity of all five switches is 100 operators, the last position finder switch being associated with the last group of 20 operators will only function when an operator in that group is seeking 45 to establish a call to the office shown in Fig. 8. In case the operator initiating the call is in the last group, the lead corresponding to 625 associated with the last bridge network (it should be observed that there is a total 50 of 5 leads similar to the lead 625, one for each group of 20 operators) will unbalance the last bridge network 236 in which case relay 237 will operate in turn operating relay 238. Relay 238 operated will close a circuit to operate relay 598 as follows: battery, winding of relay 598, 241, 231, 254, 260, 213, 212, to ground. Relay 598 operated, will function in general in the same manner as 55 relay 508 whose functions have already been described, and in addition will close a circuit

for the stepping magnet 597 associated with the last position finder switch causing this switch to rotate instead of the first position finder switch associated with the stepping magnet 536.

70 Trunk hunting.

It should be observed that while the position finder switch was hunting for the particular calling position, the sender selector and trunk finder switches were respectively hunting for an idle sender and an idle outgoing trunk in the manner hereinafter described.

75 If a particular outgoing trunk similar to that shown in Fig. 8 is busy, there will either be a plug in the trunk jack corresponding to jack 807 (Fig. 8) in which case the relay in the sleeve of the trunk circuit corresponding to relay 806 will be operated thereby connecting ground by way of 808, and 431 to the associated terminal of the arc 411, or the relay corresponding to relay 438 will be operated to connect ground to the brush corresponding to brush 421. In either case if brush 421 is resting upon the terminal of a busy trunk there will be ground on the corresponding terminal of the arc 411. An operating circuit for the stepping magnet 426 is now closed as follows: battery, winding 80 of stepping magnet 426, 427, 428, 328, 307, 313, 323, 429, 434, 435, 436, 322, 312, 316, 317, 437, 421 to ground on the hunting terminal of the trunk upon which the brush 421 is now resting. The ground on this hunting 85 terminal short-circuits relay 438 whose winding is also connected to ground at contact 439 of relay 417 thus preventing relay 438 from operating at this time. The stepping magnet 426 in operating opens at 427 its own operating circuit and releases, thus stepping its brushes 410 to 415 inclusive one step to the terminals of the next trunk in the group. This cycle of operations 90 continues until an idle trunk is found at which time the hunting lead corresponding to lead 431 will be free from ground. When an idle trunk, which we will assume to be the one shown in Fig. 8 is found, the ground which previously short-circuited relay 438 is removed 95 permitting this relay to operate in series with the stepping magnet 426, but the stepping magnet 426 will not reoperate due to the high resistance of the winding of relay 438 in series with it. Relay 438 operated connects ground at 435 by way of 436, 322, 312, 316, 317, 437, 421, to 431, causing the trunk selected to test busy to all other trunk finders in the group. It is necessary to connect this ground to the lead 431 to cause the 100 trunk to test busy because the busy ground on the lead 809 under control of relay 806 will not be supplied until the operator inserts the plug 10 of the cord circuit (Fig. 1) in the trunk jack 807 (Fig. 8) as hereinafter 105

described. Relay 438 operated closes a circuit to operate relay 474 as follows: battery, winding of relay 474, 571, 570, 475, 473, 472 to ground.

5 *Indicating the trunk number.*

After the trunk and the position have been found it is necessary to designate to the operator the number of the trunk selected.

10 This is accomplished by means of a group of lamps associated with her position the proper lamps being lighted to indicate the trunk number.

It has been determined that 160 trunks between offices is a reasonable number to allow under the worst traffic conditions between busy offices, hence this circuit is arranged to indicate the number of any trunk from 0 to 159. Each trunk finder switch is 20 arranged to hunt over a trunk group of not exceeding 20 trunks, hence under the worst traffic conditions eight trunk selector switches would be required in order to obtain a maximum of 160 trunks. For the purpose 25 of illustration only two trunk finders having a maximum of 40 trunks have been shown, but the explanation which follows applies to any number of groups comprising from 1 to 160 trunks as required, the only difference 30 being in the amount of equipment used.

Assuming that the trunk picked is in the first group and is trunk No. 10 as shown by the position of the trunk leads in Fig. 4 of the drawing, it will be necessary to indicate to the operator that trunk No. 10 has 35 been selected. In this case the brushes 310 to 315 of the steering switch will be resting upon the fourth terminal of their respective arcs, in which position the first trunk finder 40 switch is used. The operation of relay 474 connects leads 722 and 721 of the trunk number indicator (Fig. 7) by way of leads 622 and 621, leads 506 and 507, brushes 544 and 545 of the position finder switch, leads 590 and 591, 490 and 491, 492 and 493, 494 and 495, 324 and 325 to brushes 314 and 315 of the steering switch. In this case brush 314 resting on the fourth terminal of the steering 45 switch encounters an open circuit condition and lead 622 remains open. A circuit is closed, however, over lead 621 as follows: ground through the left winding (high resistance) of relay 480, brush 315, 325, 495, 493, 4010, 491, 591, brush 545, 507, 621, 721, 55 732, right winding of relay 709, right winding of relay 713, 725, 720, 620, 630, 631, to battery. Relays 480 (Fig. 4) 709 (Fig. 7) operate but relay 713 being marginal does not operate due to the high resistance of 60 the winding of relay 480 in series with it. Relay 709 operated, locks through its left winding by way of 745, 724, 624, and 647 to ground. With relay 709 operated, a circuit is closed to operate relay 704 which is 65 signed to be slow to operate and which operates and closes an obvious circuit to operate relay 703. Relay 703 is likewise designed to be slow to operate. Relay 703, operated, transfers the leads 722 and 721 to the windings of relays 710 and 714, and of 711 respectively. Relays 703 and 704 are made slow to operate so that when relay 709 operates closing the operating circuits for relays 703 and 704 in succession to transfer the leads 721 and 722, the transfer of the register 70 75 relays will be delayed until after relays 480 and 481 in the link circuit (Fig. 4) are fully operated preparing the circuit for relay 482 which will operate later to transfer the leads 492 and 493 (Fig. 4) to the next 80 succeeding resistance network of the register control combination. By transferring the register leads 721 and 722 first, no difficulty is experienced because each transfer in the register circuit (Fig. 7) changes the 85 circuit condition from battery to ground or from ground to battery as the case may be, and as each succeeding resistance network of the control combination (Fig. 4) reverses the battery and ground connections applied 90 to leads 722 and 721, completing the transfer in the register circuit before completing the transfer in the link circuit only results in connecting battery to a battery circuit, 95 or ground to a ground circuit as the case may be, the succeeding group of register relays (Fig. 7) is not affected. It is only when the transfer is completed in the link circuit (Fig. 4) that the next succeeding 100 group of register relays are capable of being operated. The operation of relay 480 in the link circuit closes an obvious circuit to operate relay 481 which locks under control of relay 474. When relay 703 finally operates relay 480 releases, closing a circuit to operate relay 482 thus transferring leads 492 and 493 in the link circuit (Fig. 4) to brushes 424 and 425 of the trunk finder switch. Brushes 424 and 425 have taken the 105 same setting as the brushes 410 to 413 inclusive, which in this case will be the eleventh terminal of their respective arc which corresponds to trunk 10.

The eleventh terminal of arc 414 is not connected to the resistance network, hence 115 lead 622 remains open, preventing either relay 710 or relay 714 from operating. But a circuit is closed over lead 621 to operate relays 711 and 483 as follows: ground, winding of relay 711, 732, 721, 621, 507, brush 545, 591, 491, 493, 441, brush 425, eleventh 120 terminal of arc 415, right-winding of relay 483 (high resistance), 484, 485, 486, 487, 580, 581 to battery. Relay 711 operates and locks and closes an obvious circuit to operate slow 125 operate relay 707, which in turn operates slow operate relay 706. Relay 706 operated, operates the slow operate relay 705, thus transferring leads 721, and 722 to the leads 726 and 727 leading to the relays 715, 716, 130

717 and 718. Relays 705, 706, and 707 are designed to be slow to operate to permit relay 483 to operate before leads 721 and 722 are again transferred. Relay 483 in the link circuit (Fig. 4) operated, closes the following circuit to operate relay 488: battery at armature 581 of relay 573, (Fig. 5), 580, 487, 486, 485, 484, winding of relay 488, 445 to ground. Relay 488 locks and relay 483 remains locked in series with relay 711 (Fig. 7), under control of relays 488, 482, 438 and 573 until relay 705 (Fig. 7) operates connecting battery to leads 721 and 722 thus releasing relay 483. Relay 488 now remains locked. The release of relay 483 connects solid ground by way of leads 493, 491, 591, etc. to lead 721, 732, thence by way of lead 727, to the windings of relays 715 and 717 operating these relays. Relay 715 and 717 operated switch the main battery feed for lighting the tens lamps from the even to the odd lamps. The "zero hundreds" lamp 700 will now be lighted from battery at 765, lamp 700, 734 to ground. The tens lamp (728) will now be lighted from battery at 711, lamp 728, 743, 744, 734 to ground. The units lamp 729 will now be lighted from battery at 778, lamp 729, 750, 751, 734, to ground. Hence the lamps displayed will read 010 indicating trunk number 10.

Function of the steering switch.

Assuming that at the time of trunk hunting all the trunks connected to the arc of the trunk finder switch (Fig. 4) are busy, then the stepping magnet 426 will continue to operate and rotate the brushes 420 to 425 inclusive step-by-step until they are resting upon the terminal twenty-first in each of the arcs 410 to 415 inclusive. At this time brush 421 will be resting upon the terminal 449 of the arc 411 and as this terminal will be connected to ground the circuit to operate the stepping magnet 426 (previously traced) will be again closed and the stepping magnet 426 will reoperate. The stepping magnet 426 will be prevented from releasing by the closure of the following holding circuit: battery, winding of the stepping magnet 426, 448, 329, 311, 321, 447, 424, 446, 445 to ground. A circuit is now closed to operate the stepping magnet 306 of the steering switch (Fig. 3) as follows: battery, winding of the stepping magnet 306, 308, 320, 310, 327, 444, 443, 442, 477, brush 425, 497, 440 to ground. The stepping magnet 306 opens at 308 its own operating circuit and releases, thereby rotating the brushes 310 to 315 inclusive one step in an anti-clockwise direction. When the brush 311 advances, the holding circuit for the stepping magnet 426 is opened, releasing the stepping magnet 426 and rotating the brushes 410 to 415 inclusive of the trunk finder switch one step in an anti-clockwise direction. In this po-

sition all the brushes except brush 421 are out of contact with any terminals of their respective arcs. The arc 411 has one terminal more than the other arcs of the switch. Consequently, in this position, the brush 421 is resting upon the terminal 440 and is, therefore connected to ground at that point. The brushes 410 to 415 inclusive will remain in this position and the trunk finder switch (Fig. 4) will not again be used until all of the trunks in all of the other groups to the same distant office have been hunted over.

The trunk finder switch associated with the stepping magnet 306 (Fig. 3) has access to other groups of trunks to the same office and it is now necessary to move another trunk finder switch such as the one shown in Fig. 3 from its normal position and cause it to seek an idle trunk in the next group of trunks to which it has access. In the normal position of the trunk finder switch all the brushes except the brush 341 are out of engagement with any of the terminals of their respective arcs. The brush 341, however, will be resting upon the terminal 326 and as soon as the stepping magnet 306 has advanced in the manner previously described a circuit will be closed to operate the stepping magnet 336 as follows: battery, winding of the stepping magnet 336, 337, 338, 313, 323, 429, 434, 435, 436, 322, 312, 351, 341, 326 to ground. Stepping magnet 336 opens at 337 its own operating circuit and releases, thus rotating the brushes 340 to 345 inclusive one step in an anti-clockwise direction to the terminals associated with the first trunk in the group. The trunks under control of the trunk finder switch (Fig. 3) are now tested in the same general manner as were those trunks accessible to the trunk finder switch (Fig. 4) and the cycle of operations (previously described) of the trunk finder switch (Fig. 4) will be repeated. If all the trunks of this group are busy the brushes 340 to 345 inclusive will rotate step-by-step until the last trunk in the group is passed and the twenty-first terminal in each arc is reached. In this position the stepping magnet 336 will be prevented from releasing by the closure of the following holding circuit: battery, winding of the stepping magnet 336, 339, 311, 321, terminal 346 in the arc 334, brush 344, 347, 478, 446, 445 to ground. A circuit is now closed to operate the stepping magnet 306 as follows: battery, winding of the stepping magnet 306, 308, 320, 310, 318, 319, terminal 348 in the arc 335, brush 345, 349, 479, 497, 440 to ground. The stepping magnet 306 opens at 308 its own operating circuit and releases, rotating its brushes 310 to 315 inclusive in an anti-clockwise direction and thus bringing into play another trunk finder switch not shown

and the group of trunks associated therewith.

This trunk finder switch not shown and the stepping magnet 306 will function in the general manner previously described for the trunk finder switches (Figs. 4 and 3) and the stepping magnet 306 will operate and rotate the brushes 310 to 315 inclusive another step to the leads associated with 10 another trunk finder switch. This cycle of operations continues until one of the trunk finder switches locates an idle trunk to the distant office shown in Fig. 8.

It should be observed that when all the 15 trunks to the distant office have been hunted over the trunk finder switch (Fig. 4) will again come into play and the stepping magnet 426 will advance the brushes 410 to 415 inclusive of the associated switch to the terminals 20 associated with the first trunk in its group and the cycle of operations will be repeated.

From the foregoing description it is evident that when any trunk finder switch advances to the twenty-first position, a circuit 25 is prepared for operating the stepping magnet of the trunk finder switch by way of either lead 329, or 339 etc., and the twenty-first terminal of either arc 414 30 (Fig. 4) or 334 (Fig. 3). In this position of the trunk finder switch a circuit is also prepared to operate the stepping magnet 306 of the steering switch by way of either lead 327 and the twenty-first terminal of arc 35 415 (Fig. 4) or by way of lead 318 and the twenty-first terminal of arc 335 (Fig. 3).

It is necessary to make sure that the stepping magnet of the trunk finder switch is fully operated before the brushes of the 40 steering switch advance, that is, it is necessary to insure the proper operation of the stepping magnet of the trunk finder switch before the stepping magnet of the steering switch operates. In order to insure this 45 sequence of operations the stepping magnet of each trunk finder switch is equipped with an additional pair of contact springs, such as 442 and 443 or 319, and the circuit for the stepping magnet of the steering switch 50 is not completed until one of these sets of contacts is closed. As the contacts in question are adjusted so that they do not close until the stepping magnet of the trunk finder switch is fully operated, it follows that 55 the steering switch will never be able to operate in advance of the stepping magnet of the trunk finder switch.

In order to insure the proper advance of the steering switch the holding circuit for 60 the stepping magnet of the trunk finder switch is controlled by way of brush 311 of the steering switch. Accordingly the holding circuit for the stepping magnet of the trunk finder switch is not opened until the 65 steering switch has actually advanced. So

long as the stepping magnet of the trunk finder switch is operated the associated brushes cannot advance, hence the trunk finder switch cannot return to normal until the holding circuit for its stepping magnet 70 is opened by the advance of the steering switch.

Selecting an idle sender.

When relay 417 was operated in the manner previously described a circuit was closed to operate relay 455 as follows: battery, right winding of relay 455, 457, 456 to ground. It should be understood that the 75 various terminals in the arcs 550 to 555 inclusive are connected to similarly situated terminals of the corresponding arcs of other sender selector switches. When the sender is busy, ground will be connected to its hunting terminal in the terminal arc 555 in the following manner: any terminal in the arc 555, common strapping, corresponding terminal in the arc (similar to arc 555) of the switch which 80 is retaining the sender busy, brush corresponding to 565, leads corresponding to 592, 451, 452, 450, winding of relay corresponding to 460, 461, 462 to ground. Due to the low resistance of the winding of relay 460, the busy condition described will 85 not be affected. Assuming that the brush 565 is resting upon the hunting terminal associated with a busy sender, relay 455 90 (Fig. 4) when operated in the manner previously described will lock over the following circuit: battery, left winding of 95 relay 455, 452, 451, 592, brush 565, hunting terminal of the busy sender to ground. Relay 455 operated closes an obvious circuit 100 through the right winding of relay 454 causing the latter relay to operate and lock 105 through its left winding by way of 457 and 456 to ground. A circuit is now closed to operate the stepping magnet 594 of the sender selector switch as follows: battery, stepping magnet 594, 593, 459, 458, 457, 456 to ground. The stepping magnet 594 in operating opens 110 its operating circuit at its own interrupter contact and releases, rotating the brushes 560 to 565 inclusive one step in an anti-clockwise direction. The brush 565 is arranged to bridge adjacent terminals of the arc 555 when the brush is rotating, but to make contact with one terminal only 115 when the brush is centered. Hence as long as the brush 565 encounters a grounded terminal the holding circuit for relay 455 will remain closed, and the stepping magnet 594 will continue to operate and release, rotating the brushes 560 to 565 inclusive step-by-step until the brush 565 is centered upon a terminal in the arc 555 associated with an idle sender. In this position the holding circuit for relay 455 will be opened releasing relay 455, and opening at 458 the operating 120 circuit.

When relay 417 was operated in the manner previously described a circuit was closed to operate relay 455 as follows: battery, right winding of relay 455, 457, 456 to ground. It should be understood that the various terminals in the arcs 550 to 555 inclusive are connected to similarly situated terminals of the corresponding arcs of other sender selector switches. When the sender is busy, ground will be connected to its hunting terminal in the terminal arc 555 in the following manner: any terminal in the arc 555, common strapping, corresponding terminal in the arc (similar to arc 555) of the switch which is retaining the sender busy, brush corresponding to 565, leads corresponding to 592, 451, 452, 450, winding of relay corresponding to 460, 461, 462 to ground. Due to the low resistance of the winding of relay 460, the busy condition described will not be affected. Assuming that the brush 565 is resting upon the hunting terminal associated with a busy sender, relay 455 (Fig. 4) when operated in the manner previously described will lock over the following circuit: battery, left winding of relay 455, 452, 451, 592, brush 565, hunting terminal of the busy sender to ground. Relay 455 operated closes an obvious circuit through the right winding of relay 454 causing the latter relay to operate and lock through its left winding by way of 457 and 456 to ground. A circuit is now closed to operate the stepping magnet 594 of the sender selector switch as follows: battery, stepping magnet 594, 593, 459, 458, 457, 456 to ground. The stepping magnet 594 in operating opens its operating circuit at its own interrupter contact and releases, rotating the brushes 560 to 565 inclusive one step in an anti-clockwise direction. The brush 565 is arranged to bridge adjacent terminals of the arc 555 when the brush is rotating, but to make contact with one terminal only when the brush is centered. Hence as long as the brush 565 encounters a grounded terminal the holding circuit for relay 455 will remain closed, and the stepping magnet 594 will continue to operate and release, rotating the brushes 560 to 565 inclusive step-by-step until the brush 565 is centered upon a terminal in the arc 555 associated with an idle sender. In this position the holding circuit for relay 455 will be opened releasing relay 455, and opening at 458 the operating circuit.

ating circuit for the stepping magnet 594 preventing it from reoperating. The following circuit will now be closed to operate relays 910 (Fig. 9) and 460 (Fig. 4): battery, winding of relay 910, 911, 912, brush 565, 592, 451, 452, 450, winding of relay 460, 461, 462 to ground. Relay 460 operated closes an obvious circuit to operate relay 463 and the relay 910 closes an obvious circuit to operate relay 913. Relay 463 operated connects ground by way of 465 and 464 to the winding of relay 466, but the latter relay will not operate at this time as it is short circuited by the ground supplied at 467 by relay 460. Relay 913 operated connects battery by way of 914, and 1000 to the windings of the various register relays of the register circuit (Fig. 10) for a purpose hereinafter more fully described.

The operation of relay 463 completes a circuit to operate relay 574 as follows: battery, winding of relay 574, 573, 572, 468, 469, 456 to ground. Relay 574 operated extends the registration leads 627, 628 and 629 (Fig. 6) to the leads 926, 927 and 928 respectively of Fig. 9. It is desirable to keep these two sets of leads separated until the calling operator's position and an idle sender are linked together and accordingly relay 574 which, when operated effects this purpose, is prevented from operating until the calling operator's position and an idle sender have both been found by the link circuit. The operation of relay 463 also completes a circuit for the operation of relay 470 by way of 471, 473 and 472 to ground. Relay 470 operated extends leads 432 and 433 of the outgoing trunk circuit (Fig. 8) to the leads 920 and 921 respectively of the sender (Fig. 9) to close in part the fundamental circuit for a purpose hereinafter more fully described. It is desirable to prevent leads 432 and 433 from being connected to the leads 920 and 921 until after an idle trunk circuit and an idle sender have been found and the special function of relay 470 is to keep these two sets of leads separated until the link circuit has found both an idle trunk and an idle sender.

Relay 463 also provides a holding circuit for relay 417 as follows: battery, right winding of relay 417, 496, 469, 456, to ground; and a locking circuit for relay 588 as follows: battery, windings of relays 588 and 585, 5011, 584, 489, 496, 469, 456, to ground. Relay 585 does not operate at this time, as it is short-circuited by the operating circuit of relay 588 previously traced to ground at 513 of relay 508.

Sender waiting.

Having found the sender a circuit is closed from battery, contact 914 of relay 913 in the sender (Fig. 9), lead 1000 left windings

of relays 1012 and 1011 in series, 1014, 947, brush 964, lead 927, brush 563, 5012, brush 541, 593, 627, winding of relay 616, 640, 641, 669 to ground operating relay 616 which locks by way of 642, 630, 631, to battery and extinguishes the "No sender" lamp 632 as an indication to the operator that a sender is now attached and that she may proceed to register the numerical digits of the called number. Relays 1011 and 1012 do not operate due to the high resistance of winding of relay 616 in series with them. Relay 615 operates when relay 616 operates over an obvious local circuit.

Registration.

We are now ready to depress numerical keys in accordance with the digits of the wanted number which we will assume to be 8150. The operator will proceed to depress numerical key No. 8 (608) corresponding to the thousands digit in which case a circuit will be closed as follows to operate relays 1011 and 1012: solid ground at the armature 647 of relay 619, 654, right make contacts of key No. 8, lead 627, 503, brush 541, 5012, brush 563, 927, brush 964, 947, 1014, left winding of relay 1011, left winding of relay 1012, 1000, 914 to battery. Relay 1011 which is sensitive operates whenever by a numerical key closure, a ground condition is connected to lead 927 but relay 1012 which is marginal only operates when solid ground is connected to lead 927 by the closure of a numerical key. Relay 1011 operated locks over lead 1000 to battery. A circuit is also closed to operate relays 922 and 1010 as follows: ground on the armature 647 of relay 619, 654, 674, left contact of key 608, 646, 645, lead 628, 504, brush 542, 5013, 5003, brush 564, 928, winding of relay 922, 948, brush 963, 949, 1015, right winding of relay 1010, 1000, 914, to battery. Relay 1010 locks through its windings in series. Relay 1010 operates only when solid ground is connected to lead 928; relay 922 is sensitive and operates whenever a ground condition is connected to lead 928 irrespective of the resistance of the ground condition.

It should be observed that whenever a ground condition is applied to the lead 926, relay 916 is operated.

Whenever the digit sent is higher than 5, it is necessary to operate one of the relays 1013, 1023, 1033 or 1043, as the case may be, in order to add five counting relays to the circuit so as to transmit the proper number of impulses to the distant mechanical office (Fig. 8).

Since the thousands digit is 8, it is necessary to operate relay 1013. This is accomplished in the following manner: from battery on the make contact 914 of relay 913, over the common battery lead 1000,

winding of relay 1013, first terminal of arc 955 of the recording switch, brush 965, 957, 958 to ground. Relay 1013 operated locks under control of relay 913. The operation of relay 922 also closes at 966 an obvious circuit by way of lead 967 to operate the stepping magnet 956. So long as the key 608 is depressed, relay 922 remains operated and the stepping magnet 956 cannot release but as soon as key 608 is released, relay 922 releases.

Relay 917 also operated by way of 968, 969, 977, 967, and 966 in parallel with the stepping magnet 956 to ground under control of relay 922. Relay 917 operated locks by way of 968, 969, 977, 967, 978 to ground and connects ground through its make contact by way of 978 and 967 to the winding of stepping magnet 956 to insure the stepping magnet's proper operation even though relay 922 only operated momentarily when the key 608 was depressed. Relay 917 cannot release until the stepping magnet 956 opens its interrupter contact 977 at the end of its operating stroke thus insuring the proper operation of the stepping magnet 956 no matter how short a space of time the numerical key 608 is depressed by the operator. When the stepping magnet 956 opens its interrupter contact 977, the locking circuit for relay 917 is opened and this relay releases opening the holding circuit for the stepping magnet 956 which likewise releases advancing its brushes 960 to 965, inclusive, one step in an anti-clockwise direction substituting at brush 963 relay 1020 for relay 1010; at brush 964 relays 1021 and 1022 for relays 1011 and 1012 and at brush 965 relay 1023 for relay 1013.

When key 608 is released, ground by way of lead 927, brush 964 and leads 947 and 1014 is removed from the left winding of relay 1011 and relay 1012 now locks from battery on lead 1000, left winding of relay 1012, left winding of relay 1011, 1014 and right winding of relay 1012 to ground.

We are now ready to send the hundreds digit which in this case is digit 1 and accordingly, numerical key 601 corresponding to the digit 1 is depressed. A circuit is now closed to operate relays 916 and 1020 as follows: ground at armature 647 of relay 619, 654, 674, left contact of key 601, 644, 629, 505, brush 543, 5014, 5001, brush 562, 926, winding of relay 916, 948, brush 963, second terminal of arc 953, 1090, right winding of relay 1020, 1000, 914 to battery. Relay 1020 locks through its windings in series. Relay 916 operated closes a circuit to operate relay 917 as follows: battery, winding of relay 917, 968, 969, 977, 967, 959 to ground. It also closes a circuit to operate stepping magnet 956 as follows: battery, winding of stepping magnet 956, 967, 959 to ground. Relay 917 operated locks by way of 968, 969, 977, 967 and 978 to ground. Thus, relay 917 will remain locked until the stepping magnet 956 completes its operating stroke, when 917 releases. This circuit arrangement insures the proper operation of stepping magnet 956 in case the relay 916 is only operated momentarily by the momentary depression of key 601.

When key 601 is depressed, a circuit is also closed to operate 1021 as follows: ground at armature 647 of relay 619, 654, resistance 650, right contact of key 601, 680, 627, 503, brush 541, 5012, brush 563, 927, brush 964, second terminal of arc 954, left windings of relays 1021 and 1022 in series, 1000, 914 to battery. Relay 1022 is marginal and will not operate due to the high resistance of the resistance 650 in series with it but relay 1021 which is sensitive operates and locks through its right winding by way of lead 1000.

When key 601 is released relay 916 releases. With relays 916 and 917 released, the holding circuit for the stepping magnet 956 is opened and the stepping magnet releases advancing the brushes 960 to 965, inclusive, another step in an anti-clockwise direction to the third terminal of each of the arcs 950 to 955 inclusive.

The operator having made the thousands and hundreds registration, the sender will now proceed to transmit impulses representing the thousands digit over the fundamental circuit to the distant mechanical office (Fig. 8) to set the incoming selector (IS) thereat. This operation will be hereinafter more fully described.

The key 605 corresponding to the digit 5 is now depressed in accordance with the tens digit of the desired number closing a circuit to operate relay 1031 as follows: ground at armature 647 of relay 619, 654, resistance 650, right contact of key 605, 680, 627, 503, brush 541, 5012, brush 563, 927, brush 964, third terminal of arc 954, left windings of relays 1031 and 1032 in series, 1000, 914, to battery. Relay 1031 which is sensitive operates but relay 1032 which is marginal does not operate due to the high resistance of resistance 650 in series with it. Relay 1031 operated locks through its right winding by way of lead 1000 to battery. With the key 605 depressed, a circuit is also closed to operate relay 916 as follows: ground at armature 647 of relay 619, 654, resistance 651, left contact of key 605, 644, 629, 505, brush 543, 5014, 5001, brush 562, 926, winding of relay 916, 948, brush 963, third terminal of arc 953, right winding of relay 1030, 1000, 914 to battery. Relay 1030 which is marginal does not operate due to the high resistance of the coil 651 in series with it. Relay 916 operated operates relay 917 and stepping magnet 956 which functions in the manner

previously described, and when relay 916 releases by the release of key 605 and relay 917 by the complete operation of stepping magnet 956, the circuit through the stepping magnet is opened and it releases advancing its brushes 960 to 965, inclusive, to the fourth terminal of each of the arcs 950 to 955, respectively.

We are now ready to send the units digit 10 which in this case is the digit zero and accordingly numerical key 600, corresponding to the digit zero, is depressed.

The key 600 depressed operates relay 1041 as follows: ground, armature 647 of relay 15 619, 654, resistance 650, right contact of key 600, 680, 627, 503, brush 541, 5012, brush 563, 927, brush 964, fourth terminal of arc 954, left winding of relays 1041 and 1042 in series, 1016, 986, to battery. Relay 1041 20 which is sensitive operates but relay 1042 which is marginal does not operate due to the high resistance of resistance 650 in series with it. A circuit is also closed to operate relay 922 as follows: from ground at armature 647 of relay 619, 654, resistance 651, left contact of key 600, 645, 628, 504, brush 542, 5013, 5003, brush 564, 928, winding of relay 922, 948, brush 963, fourth terminal of 25 953, right winding of relay 1040, 1000, 914 to battery. Relay 922 operates but relay 1040 which is marginal does not operate due to the high resistance of the resistance coil 651 in series with it. Relay 922 operated 30 operates relay 917 and stepping magnet 956 35 in the manner previously described.

When key 600 is released, relay 922 releases. When the stepping magnet 956 is fully operated, relay 917 releases and the holding circuit for the stepping magnet 956 40 is opened allowing the stepping magnet to release and advance the brushes 960 to 965, inclusive, one step in an anti-clockwise direction to the fifth terminal of each of the arcs 950 to 955, respectively.

Sending impulses.

An important feature of this invention is that after two digits (the thousands and hundreds) have been registered, the sender 50 will proceed to transmit the first digit and for each additional digit recorded, the sender will proceed to transmit impulses corresponding to the next succeeding digit over the fundamental circuit to the distant mechanical office (Fig. 8). One digit, however, is always held in reserve by the sender until 55 all the digits have been registered by the operator.

When the operator inserts the plug of the 60 cord 10 in the jack 807 in the manner hereinafter described, certain changes occur in the sender indicating that all the digits transmitted have been recorded whereupon the sender proceeds to transmit the digit 65 which has been held in reserve up to that

time. This will be hereinafter more fully described.

After the second digit (hundreds digit) was recorded, the brush 960 of the recording switch was advanced to the third terminal 70 of the arc 950 closing an obvious circuit to operate relay 900 through its right winding to ground at the brush 960. Relay 900 operated locks through its left winding by way of lead 987, strap terminals of the arc 952 75 of the recording switch, brush 962 to ground. Under certain conditions, relay 900 may lock by way of lead 988 and the strap terminal of arc 975 of the sending switch to ground at brush 985 in a manner hereinafter more 80 fully described.

Thousands selection.

We are now ready to transmit impulses over the fundamental circuit to the distant 85 office to set the selector switches thereat providing the fundamental circuit is closed and, accordingly, we must now test the fundamental circuit before allowing any impulses to be transmitted thereover. A circuit is closed to operate relays 929 and 811 90 as follows: battery, right winding of relay 811 (Fig. 8) trunk conductor 823, 432, 422, 498, 498', brush 561, 921, 989, winding of relay 929, 920, brush 560, 5015, 497, brush 95 423, 433, trunk conductor 822, left winding of relay 811 to ground. Relays 929 and 811 operate after the circuit is properly closed. The function of relay 811 will be hereinafter 100 more fully described.

Relay 929 tests the incoming selector (IS) (Fig. 8) as soon as the trunk circuit and an idle sender circuit are found. Relay 900 operates after the second (hundreds) digit 105 of the number of the called line has been recorded in the sender and the brushes of the recording switch have advanced to the third terminal of each of the arcs 950 to 955 inclusive. With relays 900 and 929 110 operated a circuit is closed to operate the stepping magnet 976 of the sending switch as follows: battery, winding of stepping magnet 976, 990, 991, 1017, 992, first terminal of the arc 974, brush 984 to ground. The stepping magnet 976 operated opens its operating circuit at its own interrupter contact and releases thereby advancing brushes 980 to 985, inclusive, one step in an anti-clockwise direction to the second terminal of each of the arcs 970 to 975, respectively. 115

With the brush 984 resting upon the second terminal of the arc 974, the operating circuit of the stepping magnet 976 is opened and the brushes 980 to 985 inclusive, accordingly remain at rest upon the second terminal of their respective arcs. A circuit is now closed to operate relay 946 125 under control of the interrupter 937 as follows: battery at the armature of relay 913, 986, 993, the second terminal or arc 971, 130

brush 981, 994, brushes 940 and 941, in parallel, first terminal of arc 930 and first terminal of arc 931 in parallel 907, 1007, 1037, 1001, 901, winding of relay 946, 9001, 939 to ground under control of interrupter 937. The contact 939 of the interrupter 937 is opened and closed periodically and relay 946 will not operate until the contact 939 of interrupter 937 is closed. When relay 946 operates, it connects ground to the winding of relay 925 but relay 925 cannot operate as it is short circuited by ground at the contact 939 of the interrupter 937. When ground is removed from the contact 939 of interrupter 937, relay 925 operates and locks in series with relay 946. When relay 925 was normal, the fundamental circuit was closed through the winding of relay 929 under control of contact 989 of relay 925. Contact 938 of the interrupter 937 was in parallel with contact 989 of relay 925 but so long as relay 925 was normal, the opening and closing of contact 938 of the interrupter 937 did not affect the fundamental circuit. With relay 925 operated, however, relay 929 is short circuited and releases, and the fundamental circuit is maintained closed under control of contact 938 of the interrupter 937. When the impulse relay 811 (Fig. 8) was operated it prepared an impulse circuit not shown in the incoming selector (IS).

The selector switches IS and S¹ and the connector C may be any type of switch which is set under the control of direct current impulses. We will assume, however, for purposes of this description that the switches are of the well known Strowger type.

The interrupter 937 closes its contact 939 and opens its contact 938 periodically. Since relay 929 is short circuited to prepare an impulse circuit including the impulse relay 811 (Fig. 8) at the same moment that relay 925 is operated by the opening of contact 939, the impulse circuit including relay 811 will be closed for practically the entire period during which contact 938 of the interrupter 937 is closed. It will therefore be observed that by connecting the impulse circuit under control of relay 925 in the manner described, ample time is allowed in which to properly prepare the impulse circuit of the incoming selector IS (Fig. 8) before any impulses are sent. Thus when the first impulse is sent over the fundamental circuit, the incoming selector IS will be in condition to receive it. When the interrupter 937 opens its contact 938, the impulse relay 811 releases and reproduces the impulse to initiate the primary movement of the incoming selector IS. At the same time that the contact 938 is opened, contact 939 is closed operating counting relay 1062 over a circuit as follows: battery, winding of relay 1062, 1018, 1024, to a lead

indicated by the digit three enclosed in a circle, thence by way of this lead (not shown) to the digit three enclosed in a circle, lead 1017, 1025, 1026, 1027, 1028, second terminal of arc 972 of the sending switch, brush 982, 995, 939 to ground. Relay 1062 operated locks in series with relay 1052 by way of the common ground leads 1009 and 909, first terminal of arc 934 and first terminal of arc 935 in parallel, brushes 944 and 945 in parallel to ground. Relay 1052 does not operate at this time due to the short circuit around its winding formed by the ground at contact 939 of interrupter 937. At the end of the impulse transmitted by the interrupter 937, the fundamental circuit is again closed at contact 938 and ground is removed from the contact 939. Closing the fundamental circuit reoperates the impulse relay 811 (Fig. 8). Opening the interrupter contact 939 allows relay 1052 to operate. Relay 1052 operated connects the lead 1024 to the winding of the counting relay 1063.

When the fundamental circuit is again opened by the interrupter 938, relay 811 again releases, and by closing the contact 939 relay 1063 operates over the circuit previously traced to operate relay 1062. At the end of the impulse, the fundamental circuit is again closed reoperating relay 811 impulse and permitting relay 1053 to operate in the same manner as relay 1052, previously described and the lead 1024 is now connected to lead 1019.

It will be remembered that we are transmitting the digit eight and that it was necessary to operate relay 1013 whenever the thousands digit exceeded five. The lead 1024 is accordingly extended to the winding of relay 1064 by way of 1019, 919, brush 983 of the sending switch, second terminal of arc 973, 1034, 1035, 1036 to the winding of relay 1064. When the next impulse is transmitted over the fundamental circuit, relay 1064 operates and at the end of the impulse, relay 1054 operates transferring the leads 1024 to the winding of relay 1065. This cycle of operations is repeated until, after the eighth impulse has been fully transmitted, relay 1059 operates. Relay 1059 operated opens at 1037 the holding circuit for relays 946 and 925, releasing these relays. The release of relay 925 short circuits contact 938 of the interrupter by way of contact 989 of relay 925 thus maintaining the fundamental circuit closed and preventing the transmission of any more impulses thereover. When relay 1059 operated, the fundamental circuit was maintained closed by means of the short circuit across the contact 938 of the interrupter by way of 906, 1006, 1038, 1005, and 905. This additional short circuit is provided to prevent the possibility of additional impulses

being transmitted over the fundamental circuit.

The operation of relay 1059 closes a circuit to operate the stepping magnet 930 of the timing switch TS when the interrupter 937 again closes its contacts 939 as follows: battery, winding of the stepping magnet 936, brushes 942 and 943 in parallel, first terminal of each of the arcs 932 and 933 in parallel, 995, 939 to ground. The 70 10 interrupter 937 again closes its contacts 939 as follows: battery, winding of the stepping magnet 936, brushes 942 and 943 in parallel, first terminal of arc 932 and first terminal of arc 933 in parallel, lead 908, 1008, 1039, 1008, 903, contact 939 of interrupter 937 to ground. Relay 1059 is locked under control of brushes 944 and 945 of the timing switch so that until the timing switch advances its brushes, the counting relays which are operated will remain locked. Thus, when the interrupter 937 again closes its contact 939, the stepping magnet 936 is operated over the circuit previously traced and when the contact 939 of interrupter 937 is again opened, stepping magnet 936 releases advancing the brushes 940 to 945, inclusive, one step in an anti-clockwise direction to the second terminal of each of the arcs 930 to 935 inclusive. When the brushes 944 and 945 advance, the ground lead of the locking circuit for the counting relays is opened and all the counting relays release.

30   *Function of the timing switch.*

The incoming selector switch IS is set in accordance with its primary movement under control of the eight impulses transmitted over the fundamental circuit in the manner previously described and a certain group of trunks leading to selector switches equivalent to the switch S¹ is selected. It is necessary for the incoming selector switch to hunt for and find an idle trunk in this trunk group before the next series of impulses are transmitted over the fundamental circuit under control of the interrupter 937. It is therefore necessary to render the interrupter 937 ineffective until sufficient time has been allowed to elapse for the incoming selector switch IS to hunt for and find an idle trunk.

When the stepping magnet 936 of the timing switch advances the brushes 940 to 945, inclusive, from the first terminal of each of the arcs 930 to 935, inclusive, the battery previously supplied to the winding of relay 946 by way of 986, 993, 981 is opened at brushes 940 and 941 preventing relay 946 from reoperating under control of contact 939 of interrupter 937 until brushes 940 and 941 come to rest upon the eighth terminal in each of the arcs 930 and 931. This is accomplished in the following manner: With the brushes 942 and 943 of the timing switch TS resting upon the second terminal in each of the arcs 932 and 933, the stepping magnet 936 is connected to contact 939 of the interrupter 937 and when contact 939 is again

closed, stepping magnet 936 operates as follows: battery, winding of the stepping magnet 936, brushes 942 and 943 in parallel, second terminal of each of the arcs 932 and 933 in parallel, 995, 939 to ground. The 70 75 stepping magnet 936 operates and when the contact 939 is opened it again releases advancing the brushes 930 to 935, inclusive, to the third terminal in each of their respective arcs. This cycle of operation continues until the brushes 942 and 943 come to rest upon the eighth terminal of their respective arcs when the circuit including the stepping magnet and interrupter contact 939 is opened and the further advance of the 80 85 brushes 940 to 945 is prevented at this time.

When the brushes of the timing switch TS advanced from the first to the second terminal in the manner previously described, brushes 944 and 945, while resting upon the second terminal in each of the arcs 934 and 935 closed the following circuit to operate relay 915: battery, winding of relay 915, second terminal of arc 934 and of arc 935 in parallel, brushes 944 and 945 in parallel 90 95 to ground. Relay 915 operated locks by way of its armature and front contact, armature and back contact of stepping magnet 976, 990, armature and front contact of relay 915 to ground. The stepping magnet 976 of the sending switch operates in parallel with relay 915 and opens the locking circuit for relay 915 which releases. The release of the relay opens the operating circuit for the stepping magnet 976 which releases advancing the brushes 980 to 985, inclusive, to the third terminal of each of the arcs 970 to 975, inclusive.

When the brushes 940 to 945, inclusive of the timing switch, reach the seventh terminal of each of their respective arcs, a circuit is closed to operate relay 918 as follows: from battery at the armature of relay 913, 986, 993, brush 981, winding of relay 918, seventh terminal of each of the arcs 934 and 935, brushes 944 and 945 in parallel 100 105 to ground. Relay 918 operated locks by way of its front contact, brush 980, third terminal of arc 970, third terminal of arc 950, brush 960 to ground. It will be remembered that the brushes 960 to 965 inclusive of the recording switch remain at rest on the third terminal of each of the arcs 950 to 955, inclusive, until after the third (tens) digit has been recorded in the manner previously described when they advance to the fourth terminal of each of the arcs 950 to 955 to complete circuits for recording the units digit. It is evident that as long as the brushes 960 to 965 remain at rest upon the third terminal of each of the arcs 950 to 955 that relay 918 will remain locked under control of brush 960 preventing the closure of the source of battery supplied to the winding of relay 946. So long as battery is re- 110 115 120 125 130

5 moved from the winding of relay 946, the circuit cannot be operated to transmit any more impulses to the fundamental circuit. Hence, it is necessary to advance the brushes 960 to 965 of the recording switch before relay 918 will release. This can only be 10 accomplished by completing the registration of the tens digit thus advancing the recording switch for units registration. It 15 is therefore very evident that two digits must at all times be recorded before the next succeeding digit is transmitted in the form of impulses over the fundamental circuit, or in other words, that one digit is always held 20 in reserve by the sender until another digit is recorded.

Hundreds selection.

25 After the tens digit has been recorded in the manner previously described, the locking circuit for relay 918 will be opened by the advance of the brush 960 to the fourth terminal of the arc 950 and relay 918 will accordingly release closing the battery supply to the winding of relay 946. With relay 918 released and the brushes 940 to 945, inclusive, of the timing switch at rest upon the eighth terminal of each of their respective arcs 930 to 935, inclusive, the circuit under control of contact 939 of interrupter 937 to 30 operate relay 946 is again prepared, and the next time contact 939 is closed, relay 946 operates over the circuit previously traced. When the contact 939 is opened, relay 925 35 operates, all of which has been previously described. With relay 925 operated, the fundamental circuit is again placed under control of contact 938 of interrupter 937 and when contact 939 is opened contact 938 is 40 closed, and an impulse is transmitted over the fundamental circuit.

45 A circuit is closed to operate relay 1069 under control of the latter as follows: battery, winding of relay 1069, 1070, 1071, 1072, third terminal of arc 973, brush 983, 919, 1019, to lead indicated by 1 in a circle, thence by lead indicated by 1 in a circle to lead 1044, 1045, 1046, 1047, 1048, third terminal of arc 972, brush 982, 9001, 939 to ground. Contact 938 50 is closed and contact 939 is simultaneously opened, the former closing the fundamental circuit and the latter removing the short circuit from the winding of relay 1059 which operates and locks in series with relay 1069. 55 Relay 1059 operated operates the stepping magnet 936 of the timing switch under control of contact 939 of interrupter 937 in the manner previously described in this case, by way of the eighth terminal of arcs 932 and 933 in parallel; and when contact 939 is 60 again opened it advances its brushes 940 to 945, inclusive, to the ninth terminal of each of the arcs 930 to 935. The counting relays release as brushes 942 and 943 advance. The 65 selector switch S¹ is set in accordance with

its primary movement by the impulse transmitted over the fundamental circuit and it will now proceed to select an idle trunk while the stepping magnet 936 of the timing switch under control of contact 939 advances 70 its brushes from the ninth to the fifteenth terminal of each of the arcs 930 to 935, inclusive. While brushes 944 and 945 rest upon the ninth terminal of arcs 934 and 935, relay 915 will reoperate and lock under control of the interrupter contact of the stepping magnet 976 closing the operating circuit for stepping magnet 976 which in turn will operate releasing relay 915 and advancing the brushes 980 to 985 inclusive another 75 step to the fourth terminal of each of the arcs 970 to 975 inclusive, substantially as previously described. While brushes 944 and 945 are resting upon the fourteenth terminal of each of the arcs 934 and 935 relay 80 85 918 will operate and will remain locked by way of brush 980, fourth terminal of arc 970, fourth terminal of arc 950, brush 960, to ground until upon the completion of the registration of the next digit, in this case the 90 units digit, the recording switch RS advances its brushes to the fifth terminal of each of the arcs 950 to 955 permitting relay 918 to release substantially as previously described. 95

Selection.

Units registration was completed in the manner previously described under registration and the tens digit will therefore be sent substantially as previously described except that counting relays 1060 and 1050, 1061 and 1051, 1062 and 1052, 1063 and 1053, 1069 and 1059 will operate and lock allowing five impulses to be transmitted over the fundamental circuit to the connector C (Fig. 8). The timing switch TS and the sending switch SS (Fig. 9) will function and the counting relays will release substantially as previously described and at the completion 100 105 of tens selection relay 918 will operate by way of the twenty-second terminal of arcs 934 and 935, and lock by way of the fifth terminal of arc 970 and fifth terminal of arc 950 to ground at brush 960. 110 115

The only digit remaining to be sent to complete "selection" is the units digit and as the sender will not transmit a digit unless two digits are recorded therein, units selection will not take place at this time. 120

Relay 918 will remain locked until the brush 960 of the recording switch advances as hereinafter described.

Units selection.

125 Before units selection can proceed it is necessary to indicate to the sender that all the digits required have been recorded. This is accomplished when the operator inserts the plug 10 of the calling cord (Fig. 1) into 130

the jack 807 of the outgoing trunk circuit (Fig. 8).

Let us assume that the operator has written up all the digits of the called line 8150 and that impulses corresponding to the digits 8, 1 and 5, have been transmitted over the fundamental circuit setting the switches IS and S¹, and the connector switch C in accordance with its primary movement. Ac-

cordingly, when the plug 10 of the calling cord is fully inserted in the jack 807, relay 810 operates in series with relay 15 in the calling cord (Fig. 1). The operation of relay 810 closes a circuit to operate relay 499

as follows: battery, winding of relay 801, 818, 430, brush 420, 4011, winding of relay 499 to ground. Relay 499 operates, but relay 801 does not operate at this time due to the high resistance of the winding of relay

499 in series with it. Relay 499 operated closes an obvious circuit to operate relay 4000. Relay 4001 operated by way of leads 476 and 521 when relay 523 was operated in the manner previously described under

“operating link circuit”. Relay 4000 operated opens the circuit for relay 4001, but the latter, being slow to release, does not release immediately but remains operated long enough to send a ground impulse over lead

926 of the sender to operate 916 as follows: from ground at contact 522 of relay 523, 521, 476, 4002, 4003, 4004, 582, brush 562, 926, winding of relay 916, 948, brush 963, fifth terminal of arc 953, 996 to battery at the front contact of relay 913. Relay 916 operated closes a circuit to operate relay 917 as follows: battery, winding of relay 917, 968, 969, 977, 967, 959 to ground. Relay 917 operated locks by way of 978 to ground and

closes a circuit to operate the stepping magnet 956 of the recording switch R. S. as follows: battery, winding of stepping magnet 956, 967, 978 to ground. Stepping magnet 956 operated opens the locking circuit for relay 917 which releases in return releasing stepping magnet 956 and the brushes 960 to 965 inclusive, are advanced one step to the sixth terminal of each of the arcs 950 to 955 inclusive.

The resistance in series with the lead 996 is substituted for the windings of those register relays which are omitted from the drawing (Fig. 10). It will be remembered that the sender may be equipped with any number of groups of register relays from one group to seven groups. Only four groups of register relays are shown in Fig. 10 and it is necessary to insert the resistance in series with the lead 996 to represent any groups of register relays which are omitted.

Relay 918 was locked in the manner previously described under “tens selection” and when brush 960 of the recording switch advances to the sixth terminal of the arc

960 the locking circuit for relay 918 is opened and relay 918 releases, closing the battery supply lead to the winding of relay 946. It will be remembered that so long as the battery supply is removed from the winding of relay 946, that impulses cannot be transmitted over the fundamental circuit.

Relays 946 and 925 now operate in sequence under control of the interrupter 937 in the manner previously described and the series of impulses corresponding to the units digit are transmitted over the fundamental circuit. The counting relays function substantially as previously described to count ten impulses before rendering the interrupter 937 ineffective. When the proper number of impulses have been transmitted, relays 946 and 925 release under control of relay 1059, and the stepping magnet 936 of the timing switch is operated by way of brushes 942 and 943 substantially as previously described, until the brushes 940 to 945 inclusive are resting once more upon the eighth terminal of each of the arcs 930 to 935 inclusive.

Discharging sender.

It will be observed that all those terminals of the arc 973 which are vacant due to the absence of certain groups of register relays from the circuit shown in Fig. 10 are connected to ground.

With the brushes 980 to 985 resting upon the fifth terminal of each of the arcs 970 to 975, a circuit will be closed by way of the fifth terminal of arc 972 to operate relays 923 and 997 as follows: battery, windings of relays 923 and 997 in parallel, leads 904 and 1004, 1073, 1002, 902, break contact of relay 925, brush 982, fifth terminal of the arc 972 to ground. Relay 997 operated opens at its back contact the battery previously supplied by way of 993 and brush 981 to the windings of relays 918 and 946 thus preventing relays 918, 946 and 925 from operating so long as relay 997 is operated. Relay 923 operated, locks by way of 998 and brush 962 to ground. It will be remembered that the brush 962 of the recording switch RS is at this time resting upon the sixth terminal of arc 952. Relay 923 operated, connects solid ground to lead 912 and closes a circuit to operate relay 924 through its right winding. Connecting solid ground to the lead 912 short circuits the winding of relay 460, (Fig. 4) by way of 592, brush 565, 451, 452 and 450, and relay 460 releases. It will be remembered that relay 460 was previously operated in series with relay 910 (Fig. 9).

Relay 924 operated opens the circuit to the winding of relay 910 which slowly releases. Relay 910 released closes a circuit to operate stepping magnet 956 of the re-

cording switch RS as follows: battery, winding of stepping magnet 956, 977, 969, make contact of relay 923, break contact of relay 910, arc 951, brush 961 to ground. Relay 923 is locked under control of brush 962 of the same switch to ground and as this brush passes from terminal to terminal of the arc, the circuit through relay 923 may be opened momentarily but as relay 923 is designed to be slow to release, it will not release under this circuit condition. The brushes of the recording switch will advance until they come to rest upon the twelfth terminal of each of the arcs 950 to 955 which is a normal position of the switch. The release of relay 910 opens the circuit through relay 913 which releases. The release of relay 913 releases the various register relays (Fig. 10) which are operated.

20 A circuit is now closed to operate the stepping magnet 976 of the sending switch SS as follows: battery, winding of the stepping magnet 976, 990, make contact of relay 923, terminals of arc 974, brush 984 to ground. The stepping magnet 976 will function over the circuit traced advancing the brushes 980 to 985 inclusive from terminal to terminal until a normal position is reached which in this case is the twelfth terminal of each of the arcs 970 to 985.

25 Relay 923 remains operated by way of brush 982 until the sending switch SS returns to normal and locks by way of brush 962 until the recording switch RS returns to normal. When the sending and recording switches have returned to their normal positions, the holding circuits for relay 923 are opened at brushes 962 and 982 and relays 997 and 923 release.

30 The release of relay 923 removes solid ground from the lead 912 thus removing the short circuit from the left winding of relay 924. Relay 924 will remain locked by way of lead 912 brush 565, 592, 451, 452 and left winding of any relays similar to relay 455 which will be connected to the lead 912 if another link circuit or circuits in hunting for an idle sender is or are passing over the terminals associated with this sender at the time relay 923 releases.

35 Due to the low resistance of the left winding of relay 924, the sender would test "busy" under this circuit condition, hence until relay 924 has been released the sender cannot again be seized by any other link circuit.

40 If the lead 912 of the sender is not being tested by another link circuit, the holding circuit for relay 924 through its left winding will not be provided, and relay 924 will accordingly release restoring the sender to normal thus rendering it available for immediate use by any other link circuit.

45 The brushes 560 to 565, inclusive of the sender selector switch remain at rest upon

the terminals of the sender leads used but as the various leads from the brushes 560 to 565, inclusive, will be opened as hereinafter described, any other link circuit may seize this sender after it becomes idle without interference due to the presence of any possible bi-path over the link circuit shown in Figs. 4 and 5.

Establishing connection.

Having completed "selection" we are now ready to establish the circuit between station 1 (Fig. 1) and station 800 (Fig. 8).

When solid ground was connected to lead 912 by the operation of relay 923, relay 460 releases permitting relay 466 to operate in series with relay 463 by way of 464 and 465 to ground. Relay 466 operated connects ground through the low resistance 4008 and contact 4011 to the brush 420 thence by way of 430, and 818 to the winding of relay 801. Relay 801 is marginal and did not operate in series with relay 499, but due to the low resistance of the coil 4008 now connected in parallel with relay 499, relay 801 operates and locks under control of relay 806. Relay 801 locked short circuits at 808 the winding of relay 499 and this relay in turn releases relay 4000. The operation of relay 801 extends the calling cord of the operator's cord circuit (Fig. 1) through the outgoing trunk circuit over the trunk conductors to the connector switch C (Fig. 8) at the distant mechanical office.

The called party is signaled in a manner not shown but which is well known in the art, and upon responding the battery supplied from the mechanical office is reversed in a manner not shown operating the polarized relay 802 in the trunk circuit (Fig. 8) thus increasing the resistance of the sleeve of the outgoing trunk circuit by removing the short circuit from the right winding of relay 806. The increased resistance of the sleeve causes the supervisory lamp 12 in the calling cord to be extinguished as an indication that the called station has answered.

Discharging operator's position.

When relay 4000 (Fig. 4) operated, it opened at 401 the locking circuit for relays 509 and 575 which released. The release of relay 509 opens at 577 a circuit through the windings of relay 405 (Fig. 4) and 614, in parallel with 613 and 619 (Fig. 6) in series, releasing these relays. The release of relay 619, releases all operated relays in the indicating circuit (Fig. 7) extinguishing the display on the number indicating lamps (Fig. 7), thus restoring the indicating circuit (Fig. 7) to normal.

Relay 619 released also unlocks and releases relays 611, 612, 615 and 616. The release of relay 613 connects solid ground to

leads 626 and 502 closing the circuit to re-operate relay 538 as follows: battery, left winding of relay 538, 5016, 547, 548, 549, 559, brush 540, 502, 626, 649, 659 to ground. 5 Relay 538 operated locks through its right winding over the circuit traced to ground at 659. It will be remembered that relay 539 is locked through its right winding by way of 521, 522 to ground. Relay 538 locked 10 operates the stepping magnet 536 over the following circuit: battery, winding of stepping magnet 536, 555, 558, 568, 578, 569, 579, 589 to ground. The brushes 540 to 545 inclusive, are advanced one step to the next 15 terminal of each of the arcs 930 to 935, inclusive. If the operator's position equipment connected to the next set of terminals is idle, ground at the back contact of relay corresponding to relay 613 will be connected 20 by way of a lead similar to lead 502 to the terminal in the arc 530. If the position equipment is busy, ground will be connected to the terminal of the arc, by way of brush corresponding to brush 540, lead corresponding 25 to lead 559, contacts corresponding to 549 and 548, lead corresponding to lead 547, contact corresponding to 557, leads corresponding to 556 and 406, winding corresponding to winding of relay 405, leads corresponding to 407, 567, contacts corresponding to 577 and 587, to ground. If some other position finder switch is finding a calling 30 position in the same group at the moment that the brush 540 comes to rest upon the third terminal of arc 530, the absence of ground thereon under this condition will permit relay 538 to release momentarily until when the position is found ground is connected to the terminal of arc 530 in the manner 35 previously traced for a busy condition when relay 538 will reoperate and lock in the manner previously described.

In any event, the stepping magnet 536 45 will ultimately cause the brushes 540 to 545, inclusive, to advance to the twenty-first terminal of each of the arcs 530 to 535, inclusive. With brush 540 resting on the twenty-first terminal of arc 530, relay 538 locks 50 through its left winding in series with the winding of relay 583, operating relay 583. Relay 583 operated opens at 589, the locking circuit (previously traced) for relay 508 causing the latter relay to release. The release of relay 508 prevents the stepping magnet 536 from reoperating at this 55 time. Hence, the brushes 540 to 545 remain for the present upon the twenty-first terminal of each of the arcs 530 to 535, inclusive. Relay 508 released opens the locking circuit for relay 523 which releases. When relay 508 released, the circuit through the right winding of the relay 538 and relay 583 in series was opened releasing relay 538, 60 and the winding of stepping magnet 536 was connected in series with the winding of 65

relay 583 as follows: battery, winding of the stepping magnet 536, 555, 549, 559, brush 540, twenty-first terminal of arc 530, winding of relay 583 to ground. Relay 583 remains operated over this circuit but the stepping magnet 536 will not operate due to the high resistance of the winding of relay 583 in series with it. Relay 523 released short circuits the winding of relay 583 which releases. This short-circuit reduces the resistance in series with the stepping magnet 536 thus permitting the stepping magnet to operate and advance the brushes 540 to 545 inclusive, to the next position of the position finder switch. In this 70 position, brushes 541 to 545, inclusive, are opened, brush 540 alone resting on terminal 596 of arc 530 thus placing the position finder switch in readiness for use when the link circuit is again seized. The release of relay 523 opens the locking circuit for relay 539 which releases.

The position is thus discharged, and rendered available for handling another call.

Discharging link circuit.

The operation of relay 4000 opened the locking circuit for relays 509 and 575, releasing these relays as previously described under "discharging operator's position."

When relay 801 locked under control of relay 806, the winding of relay 499 was short circuited at 808 and relay 499 released, opening the circuit for relay 4000, which likewise released as previously described under "establishing connection." With relays 4000 and 509 released, the holding circuits for relay 417 are opened and relay 417 releases, opening the locking circuits for relays 438, 454, 463 and 466, which also release. Relay 575 released, releases relay 474 (Fig. 4) which, in turn releases relays 481 and 488. Relay 481 released, releases relay 482, and the release of relay 463 releases relay 470, thus restoring the link circuit to normal.

Disconnection.

When the receiver is replaced upon the switchhook at substation 1, the supervisory lamp 17 is lighted. Similarly, when the receiver is replaced on the switchhook at substation 800, supervisory lamp 12 is lighted.

When the plugs 6 and 10 (Fig. 1) are removed from the jack 5 and jack 807 (Fig. 120 8) all operated relays release and the circuit is restored to normal.

Mutilated calls.

In order to prevent the operator from 125 mutilating the call in case she depresses a numerical key before the sender is attached (i. e. before relays 616 and 617 operate and lamp 632 is extinguished) a signal is provided to indicate to the operator that the 130

call is being mutilated. When a numerical key is thus depressed, a circuit is closed from battery, left winding of relay 617, thence either by way of 643 and lead 644 to keys 601, 602, 603, 604 or 605 or by way of 645 and lead 646 to keys 600, 606, 607, 608 or 609, thence either by way of 654 and 647 to ground, or by way of 656 to ground, operating relay 617. Relay 617 operated 10 locks through its left winding by way of 640, 641 and 669 to ground; and closes an obvious circuit by way of 655 to the interrupter 654, causing the "no sender" lamp 632, to flash as an indication to the operator 15 that a numerical key has been depressed before a sender is available. Upon receiving this signal the operator depresses the office key "to wipe out" the call (in the manner hereinafter described), in which 20 case another link circuit would be automatically allotted and the call would be commenced all over again. It should be observed that depressing the office key not only wipes out the mutilated call but effects a new call. 25

Wipe out.

In case the operator in writing up the call number depresses the wrong office or 30 numerical key, it is necessary to destroy the setting recorded and depress the keys all over again to obtain the correct setting. To do this the operator holds down the office key 610, operating relay 618, which opens 35 the circuit of relay 619, which releases, in turn opening the circuit of relays 611 and 612 which release. The release of relay 618 also opens the circuit including relay 405 and relays 613 and 614, which release. The 40 release of relay 405 releases the link circuit (Figs. 4 and 5); and removes the short circuit from the winding of relay 585, which operates over the following circuit: battery, winding of relays 588 and 585 in series, 584, 45 489, 496, 469, 456 to ground.

Relay 585 operated connects solid ground by way of 5000 and 5001, brush 562, lead 926, winding of relay 916, 948, brush 963 to battery at one of the terminals of arc 953; 50 and by way of 5002, 5003, brush 564, lead 928, winding of relay 922, 948, brush 963, to battery at one of the terminals of the arc 953. The operation of relays 916 and 922 over the circuits traced, operates relay 55 923 to dismiss the sender substantially as previously described under "discharging sender".

Retaining the office key 610 depressed causes relay 618 to operate, releasing relays 60 619, 611 and 612, as previously described. When relay 611 releases, relay 618 releases and relays 619 and 618 will now reoperate by way of ground on the make contact of the office key 610. The operation of relays 619 65 light the "no sender" lamp 632 as an

indication that the operator may now release the office key.

Relay 618 is made slow to release, so that after its operating circuit is opened by the release of relay 611, it will not release immediately, but will remain operated long enough to prevent relay 619 from reoperating until the register relays of the indicator (Fig. 7) have an opportunity to release. The reoperation of relay 619 causes a call 75 to be initiated all over again in the same manner as an entirely new call.

Call abandoned by positive act of the operator.

In case the operator desired to abandon the call she depresses key 652, operating relay 618, thus causing the release of relay 619 and all other operated relays. When 80 relay 405 releases, relay 585 operates and the sender is discharged in the manner previously described under "wipe out".

Call abandoned by failure on the part of the operator to proceed.

After relay 523 operates in the manner previously described under "operating link circuit", a circuit is closed to operate the dash-pot relay 408 in the manner previously 95 described under "finding the operator's position". The dash-pot relay 408 is designed to operate very slowly so that, if the call progresses properly, the link circuit will be discharged before relay 408 operates.

It is only when the call does not progress in the proper manner that relay 408 will have sufficient time to operate and close an alarm circuit in a manner not shown.

In case the operator fails to complete the writing up of the number, or completely 105 writes up the number but fails to insert the plug 10 in the jack 807, of the outgoing trunk, the dash-pot relay 408 will finally operate and in doing so short-circuits the winding of relay 405, which releases. The 110 release of relay 405 removes the short-circuit from the winding of relay 585 which now operates and discharges the sender by grounding leads 926 and 928 in the manner previously described under "wipe out".

Since the impulses corresponding to the last digit of the called number are not transmitted over the fundamental circuit to the distance office until after the plug 10 is inserted in the jack 807, it is obvious that in 120 case of a "wipe out" or an abandoned call the called party cannot be signaled falsely under any circumstances. It is only after the plug 10 has been inserted in the jack 807 for a reasonable interval of time that 125 the connection is established to the called line and signaling takes place.

What is claimed is:

1. A register sender comprising a group of registers, means for variably setting one 130

or more registers in succession, means responsive to the setting of the second register for sending a train of impulses in accordance with the setting of the first register, and means independent of the register setting device for sending a train of impulses in accordance with the setting of the register last set.

2. A register sender comprising a group of registers, means for variably setting one or more registers in succession, means responsive to the setting of a subsequent register for sending a train of impulses in accordance with the setting of the preceding register, and means independent of the register setting device for sending a train of impulses in accordance with the setting of the register last set.

3. A register sender comprising a group of registers, means for variably setting one or more of the registers in succession, a trunk circuit, means for associating the register sender with the trunk circuit, and means responsive to the seizing of said trunk circuit by an operator after the desired number of registers have been set for releasing the register sender.

4. A register sender comprising a group of registers, means for variably setting one or more registers in succession, a plurality of trunk circuits each terminating at one end in a jack, means for associating the register sender with any trunk circuit; means responsive to the setting of the second register for sending a train of impulses, in accordance with the setting of the first register, over said trunk circuit; and means, operable when a plug is inserted in the trunk jack, for sending a train of impulses over said trunk circuit in accordance with the setting of the register last set.

5. A register sender comprising a group of registers, means for variably setting one or more registers in succession, a plurality of trunk circuits each terminating at one end in a jack, means for associating the register sender with any trunk circuit; means responsive to the setting of a subsequent register for sending a train of impulses, in accordance with the setting of the preceding register, over said trunk circuit; and means, operable when a plug is inserted in the trunk jack, for sending a train of impulses over said trunk circuit in accordance with the setting of the register last set.

6. In a switching mechanism, a plurality of selectors, a steering switch, means for associating the steering switch with any selector, means controlled by the steering switch for moving the selector so associated off normal, means controlled by the steering switch operable preparatory to returning the selector to normal; and means responsive to said preparatory operation for advancing the steering switch to associate it with the next selector.

7. In a switching mechanism, a plurality of selectors, a steering switch, means for associating the steering switch with any selector, means controlled by the steering switch for moving the selector so associated off normal; means controlled by the steering switch operable preparatory to returning the selector to normal, and means responsive to said preparatory operation for disassociating the steering switch from said selector and associating it with another selector whereby the selector first mentioned is returned to normal.

In witness whereof, I hereunto subscribe my name this 12th day of June A. D. 1924.

HENRY B. BROWN.
